SUBMARINE SIGNALING APPARATUS

Theodor Bernhard Schmutte, Atlas-Werke, Bremen, Germany, assignor to Submarine Signal Company, Boston, Mass., a corporation of Maine

Application March 26, 1932, Serial No. 601,419
In Germany May 13, 1931

13 Claims. (Cl. 181—0.5)

The present invention relates to a system for submarine signaling and in particular to a system in which a group of sound receivers mounted on a so-called sword may be projected through

5 the bottom of the vessel into the water and also be withdrawn again automatically by such machinery as will be capable of being operated even though the sword should be fouled or stuck.

The difficulty experienced with prior mechanisms of this nature is that quite frequently the sword carrying the receiving apparatus may be fouled by logs or by the vessel scraping a sand bar, or in other ways, and that thereafter in attempting to retract the sword into the vessel it 15 frequently happens that the operating mechanism is jammed to such an extent that it is considerably damaged and can not thereafter be used.

In the present invention this is overcome by 20 the use of magnetic coupling elements which allow sufficient slip so that if it is impossible to work the sword up or down, the mechanism will turn around and nothing else will happen.

The present invention under normal conditions 25 may be operated automatically or manually or by combined automatic and manual means. The operation of the mechanism comprises, if the sword is retracted within the vessel, first opening a gate or shutter and then driving the sword 30 through a shaft into the water. In withdrawing the mechanism from the water the sword is first retracted and then the gate is closed. Various indicating mechanisms are provided to indicate the position that the apparatus may be in.

35 The whole mechanism may be operated by three push buttons, one designated A which is operated for projecting the sword into the water, another designated E which is used to withdraw the sword, and a third designated H which is used to provide manual operation. In the system described in the present specification when 40 one operation takes place it is impossible for the opposite mechanism to be operated and in this way absolute safety is insured.

45 Three groups of switch mechanisms are provided; the lower group indicated in the drawing providing the direct and reverse drive of the motor, the middle group providing the switches operated by the limit control elements, and the third or upper group providing the switch elements for 45 operating the magnetic coupling means.

Without further describing the general features and advantages of the present invention, 50 the invention will be described in connection 55 with the drawing in which Figure 1 illustrates

the entire schematic operating mechanism and Figure 2 indicates a detail on the line 2—2 of Figure 1 showing the shutter for operating the sword.

In Figure 1 of the drawing 10 denotes a projecting device including a piston 60 and a sword for supporting underwater sound receiving or transmitting apparatus; 11 indicates the driving spindles for moving the sword; 12 a pair of meshing gears for operating the driving spindles; 13 a cylinder or casing in which the sword can be retracted and 13' the housing for a sluice or shutter through which the casing can be shut off from the outer water. 14 and 15 are spindles for driving the shutter operating mechanism; 16 a shaft for driving the sword spindles and 17 a shaft for driving the shutter spindles.

L₁ is a screw thread upon the spindle 16 and L₂ a screw thread upon the spindle 15. W₁ is a threaded collar having a projecting arm and 20 moves upon the threads L₁, and W₂ is a similar means adapted to move upon the threads L₂. W₁ and W₂ are guided in their travel so that they do not rotate with the shafts 16 and 17. E₃ and E₄ associated with the collar W₁ are switches 25 operated by the collar W₁. E₁ and E₂ are switches associated with the collar W₂ and operated by it. M is an electric motor which works into a gear box G. K₁ and K₂ are electromagnetic coupling elements. H₁ and H₂ are handwheels for the 30 hand operation of the sword spindle and the shutter spindle respectively. S₁ to S₆ are safety switches operated by coils C₁ to C₆ which control links a to k and C₇ and C₈ delay relays 35 operating switches S₇ and S₈, respectively. A, E, H are control switches, and zero, as well as 1 to 6, are junction or contact places. a to k are electrical connecting links operated in pairs by coils C₁ to C₆. s' and s' are indicating signal lamps. 18 and 19 are leads of the power network and 20 is the power switch for throwing 40 the system across the line.

The manner of operation of the projecting gear is as follows. If the switch E is closed, a current flows over the network 18 and 19, through the switch 20 when closed, the holding switch H, switch E and then to contact 1, link a over the winding of the safety relay C₁, contact point 2, end switch E₁, contact point 3 over the protecting fuse N₂ back to the network. Through this circuit the switch of the safety relay C₁ is closed and the link b is closed and c opened. As a result the power circuit is closed through the fuses P₁ and P₂, the holding switch H, the points 50 55

6, 4, b, e, the winding of C₃, point 2, E₁, 3, returning to the line fuses N₂ and N₁.

Following this, the 3 pole switch of S₃ is closed and this puts in circuit the driving motor M in 5 a determined direction of rotation, for example, a clockwise rotation. The motor drives the gears G and the two coupling magnets K₁ and K₂. By closing the circuit of the winding C₃ the line f makes contact so that the circuit for the winding 10 of the safety relay C₁ is closed through the fuses P₁, P₂, the holding switch H, point 6, 4, f, 1, a, C₁, 2, E₁, 3 and fuses N₂ and N₁ and the coil C₁ remains connected in circuit. By closing the switch S₁, simultaneously, the circuit through 15 the fuses P₁, P₂, winding S₅, i, switch S₁, end switch E₃, point 5, point 3, and fuses N₂ and N₁ is completed across the power line. As a result of this the coil of the delay relay C_{v7} is excited 20 and the relay switch S_{v7} after the proper time delay is closed, and thereby the magnetic coupling K₁ is energized. The motor now drives the shaft 16 to move the sword spindle 11.

At the closing of the switch S₅ the link k is raised so that the safety winding C₆ and therewith 25 the relay C_{v8} and the coupling K₂ can not be put in circuit as long as the coupling K₁ is active. As the shaft 16 rotates the threaded spindle L₁ is rotated and the threaded collar W₁ carrying a projecting arm is moved from the 30 switch E₄ to the switch E₃. The left electrode of the switch E₄ connects to the sword signaling lamp s'1. The right electrode removes the open circuit to the switches S₂ and S₄, as far as the switch E₄ is concerned, as soon as the moving 35 collar W₁ leaves in its motion the switch E₄, a spring tension being exerted to force the switch E₄ to its right position.

When the moving collar W₁ reaches the switch E₃, the latter becomes reversed in connection, 40 the switch being moved to the right and thereby the energizing current of the switch coil C₅ is interrupted. The switch S₅ opens and therewith the delay relay C_{v7} so that the coupling K₁ is cut out of the circuit. The link contact k is closed 45 so that the circuit for the coil of the safety relay E₃ is closed across the network, the fuses P₁ and P₂, O, winding C₆, k, the right pole of S₁, the right pole of E₃, 5, 3 and the fuses N₂ and N₁. The safety coil C₆ closes its switch, energizes the 50 time delay relay C_{v8} and puts in circuit the coupling K₂.

The motor which during the switching runs freely in the same direction now drives the shaft 55 17 for moving the shutter spindle 14 and 15 through the coupling K₂, and the moving collar W₂ which is carried on the rotating thread L₂ leaves the switch E₂ which thereupon drops to the lower position from that indicated in the drawing. The upper pole of the switch E₂ puts in circuit the signaling lamp s'2 and completes the circuit to the safety coil C₆. At the lower end of the threaded spindle L₂ the moving collar W₂ operates the end switch E₁, the lower pole of which cuts out the signaling lamp and the upper pole of which breaks the current of the safety coil C₁.

Following this, b is opened and c is shut. With 70 the opening of b, the coil C₃ has no current and the switch S₃ cuts out the motor. Through the opening of the switch S₁ the current of the network through the fuses P₁ and P₂, point O, the winding C₆, contact k, the right switch pole of E₃, 5, 3, and fuses N₂ and N₁ is broken so that 75 C₆ and, as a result, C_{v8} have no current in them,

and the coupling K₂ after several seconds is cut out of circuit.

If C_{v8} after a delayed cutting out of the circuit is again cut in, the coupling will be cut out of the circuit at a little time later than the motor so that the shutter through the dying out of the motor is securely closed. Then for the first time the coupling is opened.

The reverse operation takes place if the switch contact A is closed. In this case there is closed 10 the safety coil C₂ whereby the motor safety switch S₄ is put in circuit through d and g. Besides this, the coil C₆ is made active over the contact k and thereby C_{v8} is closed. Following the delayed operation of the switch S_{v8}, the coupling K₂ is 15 first closed after several seconds. Through the operation of the coil C₄ the motor obtains a rotation in the opposite direction counterclockwise so that the shutter is opened through the motion of the spindle 14 and 15. The moving collar 20 W₂ leaves the switch E₁ and moves to the switch E₂. As soon as the latter reaches it, through the opening of the contact of the lower switch pole E₂, the coil C₆ and therewith C_{v8} and the coupling K₂ is cut out of circuit while the motor continues 25 to run. The coil C₆ in opening closes the bar contact i and energizes thereby the coil C₅ which on its part operates the relay C_{v7} and therewith the coupling K₁. The motor now drives the shaft 30 16 to move the sword spindle and moves out the sword whereby W₁ leaves the switch E₃ and moves to the switch E₄. Arriving there the switch E₄ opens the circuit of the coils C₂ and C₄ so that both coils are cut out of the circuit. On account of the opening of S₂, S₅ and S_{v7} are 35 also opened. The coupling and the motor are thereby cut out of circuit.

Through the holding contact H the gear, if necessary, can be entirely cut out of the circuit 40 whereby the corresponding coils C₁ and C₃, and likewise C₂ and C₄ have no current through them. In such cases in which the delayed opening of the coupling can be dispensed with, naturally the relays C_{v7} and C_{v8} can be omitted or the circuits can be so arranged that C₅ and C₆ are made 45 as time-delay relays so that C_{v8} and C_{v7} can be dispensed with as time-delay relays. If the network 18 and 19 from which the power is supplied for any reason whatsoever is opened, the shaft 50 17 for the movement of the shutter spindle can be operated directly through the handwheel H₂, and the shaft 16 for the operation of the sword spindle can be operated by the handwheel H₁ directly. The coupling between K₁ and the driving gears G, likewise the coupling between K₂ 55 and the driving gear G, is thereby broken. One can insert in the coupling magnet a resistance regulator and thereby regulate the strength of the coupling either by hand or automatically.

Instead of the fuses there can be used over-load circuit relays. The gear can also be operated in such a fashion that in overloading the coupling is weakened or wholly or partly is cut out. Instead of using both shafts 16 and 17 for the 60 automatic movement of the shutter and sword spindles, respectively, by means of the electromagnetic coupling, one can also drive only one of these parts automatically while the other one can be operated by hand.

In Figure 2 the shutter 50 is indicated as moving in a groove 51 by motion of the spindle 14. This is moved when the sword is retracted to cover the opening 52 through which the sword passes.

In the system only switches A, E and H need 75

be manually controlled except the main-line switch 20.

Having now described my invention, I claim:

- 5 1. In a system for projecting gear from within a vessel and retracting the same comprising a chamber having a shutter opening to the outer medium, means for opening said shutter and means controlled by the opening of the shutter for projecting the gear into the outer medium.
- 10 2. In a system for projecting gear from within a vessel and retracting the same comprising a chamber having a shutter opening to the outer medium, means for retracting the gear from its outward position and means operated upon the retraction of the gear for closing said shutter.
- 15 3. A system for projecting gear from within a vessel and retracting the same comprising a chamber having a shutter opening to the outer medium, means for opening said shutter, means operated by the opening of the shutter for projecting the gear into the outer medium and means operated by the retraction of the gear for closing said shutter.
- 20 4. In a system for projecting gear from within a vessel and retracting the same comprising a chamber, a driving element, a piston operated by said driving element carrying said gear movable in said chamber, means for projecting said gear downwards including a magnetic coupling element elastically coupling said gear to said driving element.
- 25 5. In a system for projecting gear from within a vessel and retracting the same comprising a chamber and a shutter therefor, a piston carrying said gear adapted to move in said chamber, means for projecting said gear downwards and means for operating said shutter, both said last means being provided with magnetic elastic coupling elements for operating said gear and said shutter.
- 30 6. In a system for projecting gear from within a vessel and retracting the same, a driving motor, a spindle operated by said motor for projecting the gear, a magnetic coupling element for coupling said driving motor to said spindle and a time delay circuit for energizing said magnetic coupling.
- 35 7. In a system for projecting gear from within a vessel and retracting the same, a driving motor, a spindle operated by said motor for projecting the gear, a magnetic coupling element for coupling said driving motor to said spindle, and means for uncoupling the driving motor and stopping the same when the end positions of operation have been reached.
- 40 8. In a system for projecting gear from within a vessel and retracting the same, a driving motor, a spindle operated by said motor for projecting the gear, a magnetic coupling element for coupling said driving motor to said spindle and means for deenergizing said coupling and operating said spindle by hand.
- 45 9. In a system for projecting gear from within a vessel and retracting the same, a driving motor, a spindle operated by said motor for projecting or retracting said gear, a magnetic coupling element for coupling said driving motor to said spindle, a shutter, a spindle and second magnetic coupling element for operating said shutter and means for deenergizing either or both of said coupling elements and individual means for operating either said projecting gear or said shutter manually.
- 50 10. In a system for projecting gear from within a vessel and retracting the same, a cylinder, a piston adapted to be moved in said cylinder and carrying at its end a sound transmitting or receiving sword, a plurality of spindles operating in said piston for raising or lowering the same, a shutter and means operating said shutter to close the cylinder from the outer water when the sword is in its retracted position.
- 55 11. In a system for projecting gear from within a vessel outward to the water medium, a well, sound signaling gear, means supporting said sound signaling gear in said well, means for projecting said gear into the water medium from said well and means controlled by the position of the gear for ceasing the operation of said projecting means.
- 60 12. In a system for projecting gear from within a vessel outward to the water medium and retracting the same, a well, sound signaling gear, means supporting said sound signaling gear in said well, means for projecting and retracting said gear into the water medium from said well and returning the same and means controlled by the position of the gear for ceasing the operation of said projecting and retracting means at the two extreme positions of the gear.
- 65 13. In a system for projecting gear from within a vessel outward to the water medium and retracting the same, a well, sound signaling gear, means supporting said sound signaling gear in said well, electrical means for projecting and retracting said gear out of and into the well and means mechanically operated by said projecting and retracting means for stopping the electrical operation of the projecting and retracting means in their extreme positions.

THEODOR BERNHARD SCHMUTTE. 55
